[57] CLAIM

The ornamental design for an aerial toy, as shown and
described.

DESCRIPTION

FIG. 1 is a top plan view of a aerial toy showing my
new design, the side opposite being substantially a mir-
ror image;

FIG. 2 is a cross-sectional view thereof taken along the
horizontal reference lines in FIG. 1;

FIG. 3 is a cross-sectional view thereof taken along the
vertical reference lines in FIG. 1;

FIG. 4 is a top plan view of modified embodiment of the
design shown in FIGS. 1 through 3, the side opposite
being substantially a mirror image;

FIG. 5 is a cross-sectional view thereof taken along the
horizontal reference lines in FIG. 4;

FIG. 6 is a cross-sectional view thereof taken along the
horizontal reference lines in FIG. 4;

FIG. 7 is a top plan view of a second modified embodi-
ment of the design shown in FIGS. 1 through 3, the side
opposite being substantially a mirror image;

FIG. 8 is a cross-sectional view thereof taken along line
the vertical reference line lines in FIG. 7; and,

FIG. 9 is a cross-sectional view thereof taken along the
horizontal reference lines in FIG. 7.
